UNITED STATES PATENT OFFICE.

CARL WINKLER, OF BERNE, SWITZERLAND.

MACHINE FOR CASTING CURVED STEREOTYPE PLATES.

1,413,446.

Specification of Letters Patent. Patented Apr. 18, 1922.

Application filed January 20, 1921. Serial No. 438,804.

To all whom it may concern:

Be it known that I, CARL WINKLER, a citizen of the Swiss Republic, residing at Berne, in the Swiss Republic, have invented new and useful Improvements in Machines for Casting Curved Stereotype Plates, (for which I have filed application in Germany Sept. 8, 1919,) of which the following is a specification.

10 My invention relates to an inclined mould for casting curved stereotype plates. In opening such a mould, its lower edge, according to my invention, is moved in such a curve that the cast plate swings about its 15 top edge, which is kept in engagement with the mould core by any suitable means, such as projections, or the like, so that the plate, when the form is entirely open, will hang freely from said edge. Preferably the back, 20 or lower, piece, by which the mould is closed, is pivoted at its ends, and by suitably shaping the surface against which the back, or lower, edge of the cast plate bears, said wall is so connected to the cast plate that when 25 opening the mould it will be tilted with the plate and thus release the matrix adhering to said plate.

By this arrangement and operation the plate can be easily lifted out of the open 30 mould, and in addition to this the matrix is preserved.

In the accompanying drawing illustrating my invention by way of example,

Fig. 1 is a section through the mould in 35 closed condition,

Fig. 2, a similar section of the mould in open condition,

Fig. 3, a plan of the mould bed showing the matrix in position.

40 The mould consists of the bed *a* and cope or core *b*. In the bed *a* (Fig. 1) the matrix *d* provided with a metal border *c*, consisting of two clamped pieces, is so placed that the metal border *c* fits tightly a groove *e* of the 45 bed, whilst the side edges of the matrix fit loosely under the usual side segments *f*, and the back edge of the matrix fits loosely under the pivoted piece *g*. The inner edge of the piece *g* has a projection *h*, which, when 50 a plate is cast, forms a groove in said plate, and enables the piece *g* to be more easily tilted about end pivots by the plate when the mould is opened.

In order to open the mould, that is, to 55 move the bed out of the position shown in Fig. 1 into that shown in Fig. 2 the middle

of said bed is pulled down in an inclined straight line, whilst a pin *l* attached to the lower edge of the bed runs in a cam *m*, which so guides the bed that the plate can 60 swing about pins *n* on the core. Owing to the connection of the plate *k* with the piece *g* by the projection *h* and groove *i*, said piece *g*, on opening the mould, will be tilted by the plate, so that the edge of the matrix 65 under the piece can follow the plate. The opposite edge of the matrix, which is provided with the metal border *c*, also follows the movement of the plate, because the border can rise out of the groove in the bed. 70 In this position shown in dotted lines in Fig. 2 the plate and matrix (with or without the side pieces *f*) can be easily lifted off the core *b* so that while the pins *n* serve to permit the plate to be swung about the same 75 on the core, yet the pins *n* only act as pegs so that the plate can be easily lifted off of the same. Outside the mould the matrix is removed from the plate. If it is desired to cast a second plate from this matrix it is 80 placed in the bed again, and the metal border attached thereto, by fitting tightly in the groove in the bed, assures that the matrix will occupy exactly the same position as in casting the first plate, so that all plates 85 cast will keep good register.

What I claim and desire to secure by Letters Patent of the United States is:—

1. The improved mould for casting curved plates, comprising in combination an inclined core, a correspondingly inclined bed, means to move the middle part of said bed in a straight line away from said core to open the mould, means to attach the cast plate to the upper edge of said core, and means to guide the lower edge of said bed in a path permitting the lower edge of the cast plate to swing about its upper edge in opening said mould, substantially as, and for the purpose set forth.

2. The improved mould for casting curved plates, comprising in combination an inclined core, a correspondingly inclined bed, means to move the middle part of said bed in a straight line away from said core to open the mould, means to attach the cast plate to the upper edge of said core, means to guide the lower edge of said bed in a path permitting the lower edge of cast plate to swing about its upper edge in opening said mould, and a pivoted piece closing the back end of the mould and adapted to be

tilted by the cast plate in opening the mould, substantially as, and for the purpose, set forth.

3. The improved mould for casting curved plates, comprising in combination an inclined core, a correspondingly inclined bed, means to move the middle part of said bed in a straight line away from said core to open the mould, means to attach the cast plate to the upper edge of said core, means to guide the lower edge of said bed in a path permitting the lower edge of the cast plate to swing about its upper edge in opening

said mould, and a metal border for the upper edge of the matrix adapted when a plate 15 is being cast to fit in a groove of said bed, substantially as, and for the purpose, set forth.

In testimony whereof I have signed my name to this specification in the presence of 20 two subscribing witnesses.

C. WINKLER.
